UNITED STATES PATENT OFFICE.

FRANKLIN B. GIESLER, OF MILWAUKEE, WISCONSIN.

PNEUMATIC MALTING-DRUM.

No. 805,856.

Specification of Letters Patent.

Patented Nov. 21, 1905.

Application filed February 10, 1902. Serial No. 93,297.

To all whom it may concern:

Be it known that I, FRANKLIN B. GIESLER, a citizen of the United States, and a resident of Milwaukee, in the county of Milwaukee and 5 State of Wisconsin, have invented certain new and useful Improvements in Pneumatic Malting-Drums; and I do hereby declare that the following is a full, clear, and exact description thereof.

10 The improvements constituting my invention consist in certain peculiarities of construction and combination of parts hereinafter particularly set forth with reference to the accompanying drawings and subsequently 15 claimed, the object of said invention being to enhance the efficiency of rotatory pneumatic malting-drums.

Figure 1 of the drawings represents a central longitudinal section view of a rotatory 20 pneumatic malting-drum made to embody the improvements constituting my invention. Fig. 2 represents a detail partly-sectional view of a portion of a spraying apparatus in connection with the drum; Fig. 3, a sectional view indicated by line 8 8 in Fig. 2; Fig. 4, a sectional view of another portion of the 25 spraying apparatus, and Fig 5 a similar view indicated by line 10 10 in Fig. 4.

Referring by letter to the drawings, A indicates the main or material holding portion 30 of a pneumatic malting-drum embodying improvements in accordance with my invention, this drum being provided with outer track-rings *b* in contact with flanged wheels *d*, the 35 axles of which turn in suitably-arranged bearings. A spur-gear ring *e* on the drum meshes with a pinion *f* on a shaft *g*, carrying a spur-wheel *h*, in mesh with a pinion *i* on a shaft *j*, having a worm-wheel *k* fast thereon 40 in mesh with a worm-sleeve *m*, loose on a main shaft *B*, but engageable at one end with a clutch *C*, splined on the same shaft. A lever-controlled rod *D*, mounted in suitably-arranged bearings, has spanner connection 45 with an annular groove of the clutch, and by manipulation of the lever said clutch is thrown in and out of engagement with the worm-sleeve, the drum being in motion or at rest, according to the adjustment of the aforesaid 50 clutch.

The drum is provided with the usual and necessary openings that are normally closed, and by means of partitions *p* *q* therein, parallel to its heads, said drum is provided with 55 front and rear end chambers. Connected at their ends to the partitions to register with

corresponding openings therein are the usual perforated air-flues *G* at suitable intervals apart. The central air-flue *H*, of perforated material, is of greater area than the other flues *G* and is preferably the same in cross-section 60 as has been set forth in Patent No. 507,536, issued to me October 31, 1893, its front end being closed by one of the aforesaid partitions and its rear end open through the other partition and adjacent drum-head, to an arm of 65 an air-exhaust flue *J*, that is connected to a suction-fan casing or a draft-stack, an annular shield *r* being arranged in the rear end chamber of the drum to prevent direct flow 70 of air through flues *G* to said exhaust-flue. In some instances it may be preferable to omit the rear partition *q* of the drum and have the rear ends of air-flues *G* closed by the rear drumhead or hand-hole covers 75 thereon.

A central opening in the front drumhead registers with an arm of an air-supply flue *I*, the open end of this arm and that of the arm of air-exhaust flue *J* being flared and opposed to a flanged ring *K*, fast to the adjacent drumhead. A gasket, of rubber, leather, or other suitable material, is fastened on the flare of each flue-arm to impinge the flange *t* of the adjacent ring *K* to prevent escape of 80 air between said flue-arm and ring, provision being had in the setting of the gaskets to compensate for settle of the drum incidental to wear of various parts of the machinery.

The front ends of air-flues *G* are fitted in 85 castings *L*, having flanges riveted or otherwise rigid with the front partition *p* of the drum, and in pivotal connection with each casting-flange is a gate *M*, by which the air-supply through the adjacent flue is regulated, 95 the movement of the air being upward through the material in the drum and out through the central flue *H* of same.

The usual perforated pipes *Q*, lengthwise of flue *H* exteriorly of the same, have inturned 100 converging branches fitted to a coupling *R*, having a screw-shank *y*, Fig. 2, engaging an opening provided in drum-partition *p*, a set-nut *z* being run on the shank to hold said coupling in place. The coupling has a conical bore in which a hollow conical spigot *S* has loose fit to save wear, this spigot being provided with a large water-outlet and a series of radial steam-ports, these ports being the same in number and spacing as the aforesaid pipe branches fitted to said coupling, all 105 of which is best shown in Fig. 3.

- The rear end of the spigot S is closed and a front end nipple of said spigot is in screw-thread connection with an end of a horizontal stretch of a stationary water-conductor pipe T, the vertical stretch of which extends through a fitting on the aforesaid arm of air-supply flue I, a cock-controlled steam-pipe U being coupled to the water-conductor pipe above said fitting.
- 10 In water-tight connection with coupling R is a sleeve V, having a stuffing-box engaged by the horizontal stretch of pipe T in connection with spigot S, and this stretch of pipe is provided with a leak-port b', Fig. 2, through
- 15 which water supplied under constant pressure escapes into said sleeve to exert pressure on said spigot. The vertical stretch of pipe T is provided with a cock W, by which the feed of water from an elevated reservoir (not
- 20 shown) is controlled, and below this cock said pipe is interrupted by a casing X of a conical hollow spigot Y, provided with graduated inlets and a single outlet, this outlet being of such length as to be always open regardless
- 25 of the rotary adjustment of said spigot. As best shown in Fig. 4, the small end of spigot Y is provided with a screw-shank c', that extends through a central opening in an otherwise-closed end of the casing X, and a set-
- 30 nut d' is run on said shank to hold said spigot in adjusted position. The other end of casing X is open, and the corresponding large end of the spigot Y is provided with an angular central lug e' to facilitate its adjustment
- 35 by means of a wrench when the set-nut d' is loosened.
- Spigot Y is adjusted to regulate the flow of water from the elevated reservoir, (not shown,) and incidental to the flow the water-
- 40 pressure in the sleeve V on spigot S is sufficient to crowd the same water-tight in coupling R, there being sufficient elasticity in pipe T to permit this crowding, it being understood that this coupling and sleeve V in connection therewith turn with the drum. The water is admitted in quantity to each pipe Q while the inturned branch thereof is passing the water-outlet of said spigot between two of the steam-ports. The water under con-
- 45 stant pressure is only admitted to the sprinkling system at such times, as the moisture with the air is not sufficient for the germinating process that takes place in the drum, said water being properly attemperated.
- 50 The drum being at rest with the steam-ports of spigot S in register with the converging front-end branches of pipes Q, said drum may be readily steamed through the sprinkling system preliminary to washing out
- 55 of the same when emptied of the green malt produced therein.
- Having thus described my invention, what I claim as new, and desire to secure by Letters Patent, is—
- 60 1. A rotatory malting-drum having a coup-

ling connecting its sprinkling-pipes, a closed-end hollow conical spigot loose in the coupling and provided with a water-outlet, a water-conductor pipe coupled to the spigot, a sleeve having water-tight connection with said coupling, a stuffing-box in the sleeve engaged by the water-conductor pipe, the latter being provided with a leak-port within said sleeve, and means for circulating air in the drum.

2. A rotatory malting-drum having a coup- 75 ling connecting its sprinkling-pipes, a closed-end hollow conical spigot loose in the coupling and provided with a water-outlet as well as a series of steam-ports the latter corresponding in number and spacing to the ends 80 of the sprinkling-pipes in connection with said coupling, a water-conductor pipe coupled to the spigot, a sleeve having water-tight connection with the aforesaid coupling, a stuffing-box in the sleeve engaged by the water- 85 conductor pipe, the latter being provided with a leak-port within said sleeve, a cock-controlled steam-pipe coupled to said water-conductor pipe, and means for circulating air in the drum. 90

3. A rotatory malting-drum having a coup- 95 ling connecting its sprinkling-pipes, a hollow spigot-terminal of a stationary water-conductor pipe engaging the coupling, the spigot being provided with a series of ports in addition to a larger outlet, these ports being the same in number and spacing as the coupling ends of said sprinkling-pipes, a cock-controlled steam-pipe coupled to the former pipe, and means for circulating air in the drum. 100

4. A rotatory malting-drum having a coup- 105 ling connecting the sprinkling-pipes, a closed-end hollow conical spigot that serves as a bearing for the coupling and is provided with a water-outlet, a water-conductor pipe coupled to the spigot, means for regulating flow of water through said conductor, and means for circulating air in the drum.

5. A rotatory malting-drum having a coup- 110 ling connecting its sprinkling-pipes, a closed-end hollow conical spigot that serves as a bearing for the coupling, and is provided with a water-outlet, a water-conductor pipe coupled to the spigot, a casing in connection with said conductor, a hollow conical spigot that 115 is rotatably adjustable in the casing, this spigot being provided with a series of graduated inlets and a single outlet, said outlet being of such length as to be always open regardless of the adjustment of said spigot, and means for circulating air in the drum. 120

In testimony that I claim the foregoing I have hereunto set my hand, at Milwaukee, in the county of Milwaukee and State of Wisconsin, in the presence of two witnesses.

FRANKLIN B. GIESLER.
